Application February 19, 1953, Serial No. 23,695

Term of patent 3½ years

(Cl. D92—1)

To all whom it may concern:

Be it known that I, Annette Holland, a citizen of the United States, residing at New York city, in the county of New York and State of New York, have invented a new, original, and ornamental Design for a Textile Fabric or Similar Article, of which the following is a specification, reference being had to the accompanying drawing, forming part thereof.

In the drawing, the single figure is a plan view of textile fabric or similar article, showing my new design.

A design unit is outlined by broken lines and is repeated as indicated.

I claim:

The ornamental design for a textile fabric or similar article, substantially as shown and described.

ANNETTE HOLLAND.
